UNITED STATES PATENT OFFICE

HENDRIK AREND HIDDE NIJLAND, OF ZEIST, NETHERLANDS

AUTOMATIC ELECTRIC SWITCHING DEVICE

Application filed December 21, 1927, Serial No. 241,579, and in the Netherlands January 14, 1925.

This invention relates to an automatic electric circuit closing device for changing over the feeding point from one electric feeder to a reserve electric feeder in the event a disturbance occurs in the first mentioned feeder.

It is generally known that, in order to feed an important feeding point or consumption point in the most reliable way with electrical energy, it is usual to connect this point to two cables or feeders, leading from the same or from different generating stations to the feeding point.

However, this double connection is of questionable value if both cables, under normal conditions, are always in connection with the outgoing cable and are protected only by a usual form of safety device. Accordingly, it has been proposed to employ in conjunction with the double connection special safety systems requiring the use of auxiliary wires between the generating station and the feeding point. Usually, however, the addition of such auxiliary wires constitutes an item of quite considerable expense because the feeder cables are not provided with the necessary additional wires. The proposed construction thus is likewise possessed of various disadvantages.

The primary object of the present invention is to overcome these various disadvantages and yet provide a reliable connection by means of two feeders connecting the generating station and the feeding point. Thus, in accordance with the invention, both feeders are connected with an automatic electric circuit closing device, whereby when one feeder cable is disturbed the supply cable is automatically connected to the other feeder cable. Moreover, when the two feeders are connected in ring form, the invention provides means whereby the ring is opened directly at the feeding point in the event one branch is disturbed.

According to the invention, the proposed automatically acting circuit closing device is provided with a plurality of controlling coils which are energized to actuate suitable switch means when a disturbance occurs in one or the other of the feeder cables.

For a better understanding of the invention, reference is made to the accompanying drawings, wherein

Figure 1 is a general diagram of the invention as employed in connection with a feeding point fed by two feeders;

Fig. 2 is a diagram of the invention as employed in connection with a ring circuit;

Fig. 3 is a diagram similar to Fig. 2, showing a modified form of the invention.

Considering the drawings more in detail, Figure 1 shows two feeders 1 and 2 adapted to be connected to an outgoing cable 3. In the circuit of the feeders are arranged voltage transformers 4 and 5, the secondary coils of which are connected to coils 6 and 7 of a differential voltage relay, the armature 8 of which cooperates with contacts 9, 10, 11 and 12. The contacts 11 and 12 are interconnected and are also connected with one terminal of a suitable current source, such as a battery (not shown). The contacts 9 and 10, on the other hand, are connected respectively with one terminal of controlling coils 14 and 13 of an automatic reversing switch.

These coils actuate armatures 15 and 16, which are connected at their lower ends to a balance lever 17, provided at each end with a contact arm 18, 19, which cooperate with contacts 20, 21, 22 and 23 and thereby establish connection between the cable 3 and either the feeder 1 or the feeder 2.

In the outgoing cable 3 is connected a current transformer 25, the secondary coil of which is connected with the coil of an auxiliary relay 26. The armature of this relay is adapted to connect two contacts 27 and 28, of which contact 27 is connected to one terminal of each of the controlling coils 13 and 14, and contact 28 is connected to the other terminal of the suitable current source mentioned above. The relay 26 is so adapted that when its coil is energized, the armature is drawn up and locked in position, where it remains until released by hand or other suitable means.

Assuming a hypothetical case wherein the apparatus is in the position shown in Fig. 1, the operation of the circuit closing device will be as follows: As soon as a disturbance occurs

in the feeder 2, the voltage therein will drop below the normal value, with the result that the coil 6, energized through the transformer 4 by the normal voltage in feeder 1, will pull 5 up the armature 8 of the differential relay and close the contacts 9 and 12. Upon closing of the contacts 9 and 12, the controlling coil 14 is energized by current from the separate source and the armature 16 is pulled up, whereupon 10 the balance lever 17 is tilted and contacts 20 and 21 are closed by the contact arm 18 to establish connection between the cable 3 and the feeder 1.

In the event a disturbance occurs in the 15 feeder 1, after its connection to the cable 3, and its voltage decreases in consequence, the differential relay will drop its armature under the influence of the coil 7 and connect contacts 10 and 11, because the voltage in 20 coil 6 will then be less than the voltage in coil 7. The controlling coil 13 will then be energized from the separate current source and will draw up its armature 15 and tilt the balance lever 17 to connect the contacts 22, 23 25 by means of the contact arm 19.

On occasion, a disturbance may occur in the outgoing cable 3, and a current of high value appear in this cable. To guard against this contingency, the auxiliary relay energized by the transformed is provided. Accordingly, should a current of high value appear in cable 3, the relay 26 will be energized to draw up and lock its armature in its upper position and thus break the connection between the contacts 27 and 28 controlling the common connection between the coils 13 and 14 and the current source. So long as the armature remains in its locked position, the 35 circuit of the coils 13 and 14 remains open and 40 the circuit closing mechanism is held inoperative. Only after the armature has been released as upon disappearance of the disturbance in cable 3, will the circuit closing mechanism again become operative.

45 In Fig. 2 is indicated the diagram of a ring connection wherein 1 and 2 indicate the two feeder branches and 3 the outgoing cable branch. A by-pass or bridge connection is 50 placed about this branch point in order to connect the two feeder branches of the ring cable. In addition to the circuit closing mechanism shown in Fig. 1, the arrangement is provided with a minimum voltage switch 55 24 located in the bridge connection. The coil of this switch is so constituted that when the voltage therein drops below a predetermined value the switch will be opened.

60 In Fig. 3 an arrangement similar to that 60 in Fig. 2 is shown, with the difference that the voltage transformers 4 and 5 are employed to serve as a current source for the controlling coils 13 and 14 instead of a separate current source. The relay 26 is accordingly provided with two sets of contacts 27,

28 and 29, 30, of which one set relates to the coil 13 and the other to the coil 14.

Aside from the operation of the additional elements shown in Figs. 2 and 3, the operation of the arrangements therein illustrated 70 is the same as that of the apparatus shown in Fig. 1.

I claim:

1. The combination with a supply cable, a main feeder and a reserve feeder cable, of an 75 automatic switching device, comprising a beam oscillatable about a pivot, a switch carried at opposite ends of the beam and arranged to transfer the load from one feeder to the other, solenoids exerting, when energized, a pull upon said beam at opposite sides of its pivot, said beam being returnable by hand to its neutral position when both solenoids are deenergized, and a differential relay responsive to the electrical condition of said 80 feeder cables for selectively energizing said solenoids.

2. The combination with a supply cable, a main feeder cable and a reserve feeder cable, of an automatic switching device, comprising a beam oscillatable about a pivot, a switch carried at opposite ends of the beam and arranged to transfer the load from one feeder to the other, solenoids exerting a pull upon the beam at opposite sides of its pivot when 85 energized, said beam being returnable by hand to its neutral position when both solenoids are deenergized, a transformer in each feeder cable, a differential relay connected in circuit with each of said transformers, a 90 transformer in said supply cable, and an auxiliary relay connected in circuit with said latter transformer and arranged to de-energize said solenoids when a disturbance occurs 95 in said supply cable.

In testimony whereof, I have signed my name to this specification.

HENDRIK AREND HIDDE NIJLAND.
